UNITED STATES PATENT OFFICE.

JOHN R. THOMSON, OF NEW YORK, N. Y.

DESIGN FOR JARS FOR CONTAINING PRESERVED FISH, &c.

Specification forming part of Design No. 6,208, dated October 15, 1872.

To all whom it may concern:

Be it known that I, JOHN R. THOMSON, of the city, county, and State of New York, have invented a Design for Jars for containing Preserved Fish, of which the following is a specification:

The nature of my design is fully represented in the accompanying drawing, in which—

Figure 1 is a perspective view of a jar made according to my design; Fig. 2 is a longitudinal section thereof; and Fig. 3 is a plan of the same.

Similar letters of reference indicate corresponding parts in all the figures.

A is the jar, which is of quadrangular form in its transverse section, and parallel or of very slightly reversed taper longitudinally

from its bottom nearly to its mouth, as shown in Figs. 1 and 2 of the drawing. Near the mouth it flares outward, as shown at a, gradually on the inner side of the jar, and more suddenly on the exterior or outer side. At the mouth, on the inner side, there is formed a lip, b, within which the cork or stopple of the jar fits.

Claim.

The design for jars, substantially as represented and described.

J. R. THOMSON.
